FIG. 2. A cross-sectional view of a device assembly. The assembly includes a base 1, a central housing 2, and a top cover 3. A spring 4 is positioned within the housing 2. A lever system is shown, with a main lever 7 and a connecting lever 10. A cam 13 is attached to the main lever 7. A slot 14 is present in the housing 2. A small circular component 15 is located near the base 1. A label 8 is attached to the central housing 2. A label 9 is attached to the top cover 3. A label 16 is attached to the base 1. A label 17 is attached to the side of the top cover 3. A label 18 is attached to the top edge of the housing 2. A label 19 is attached to the side of the top cover 3. A label 20 is attached to the top edge of the top cover 3.

UNITED STATES PATENT OFFICE.

FRANK MIHALYI, OF ROCHESTER, NEW YORK, ASSIGNOR TO CROWN OPTICAL COMPANY,
OF ROCHESTER, NEW YORK, A CORPORATION.

OPTICAL INSTRUMENT.

1,285,775.

Specification of Letters Patent.

Patented Nov. 26, 1918.

Application filed August 4, 1917. Serial No. 184,463.

To all whom it may concern:

Be it known that I, FRANK MIHALYI, a citizen of the United States, and resident of Rochester, in the county of Monroe and State 5 of New York, have invented certain new and useful Improvements in Optical Instruments, of which the following is a specification.

The present invention relates to optical instruments, and more particularly to the 10 type in which prisms are employed for deflecting the optical axis of the instrument, an object of this invention being to provide means by which the prism may be adjusted on its seat without producing any stresses 15 or strains on the prism tending to distort the prism or cause the breakage thereof.

To this and other ends, the invention consists of certain parts and combinations of parts all of which will be hereinafter described, the novel features being pointed out in the appended claims.

In the drawings:—

Figure 1 shows one casing of a binocular with the cover and the eye-piece mounting 5 removed;

Fig. 2 shows a binocular casing in section, with the covers at opposite ends of the latter removed and the eye-piece mounting and objective mounting also removed;

Fig. 3 is a section on the line 3—3, Fig. 2;

Fig. 4 is a perspective view of the device which acts as a cover for the prism and also is engaged by adjusting devices; and

Fig. 5 is a detail section on the line 5—5, Fig. 3.

Referring more particularly to the embodiment shown in the drawings, 1 indicates one of the casings of a binocular provided with the usual arms 2 by which two casings 4 are connected together. These casings are usually closed by cover plates, not shown, secured by screws engaging in the openings 3. An eye-piece mounting, not shown, is generally secured by the threads 4, while an objective mounting, not shown, is secured by the threads 5. The casing has an internal partition 6 provided with three openings, while prisms 7 and 8 engage opposite sides of the partition and are arranged over the openings in such a manner that the optical axis extends from the objective through one of the openings in the partition to and

through the prism 7, thence by another opening in the partition to and through the prism 8, and thence through the third opening to 55 the eye-piece.

The prism 8 is arranged on a seat 9 so that it may partake of a longitudinal movement, but not of a lateral movement. Over this prism is arranged a device acting as a 60 cover, said device being in this instance in the form of two angularly arranged portions 10 connected by a portion 11 and provided at opposite sides with feet or flanges 12 which bear against the angularly arranged 65 faces of the prism to space the walls 10 from the prism faces so as to provide moisture evaporating spaces between the prism surfaces and the cover wall. At the outer ends of the walls 10, offset portions 13 are provided, and from these offset portions curved portions 14 extend, the curved portions conforming to and engaging the curved ends 15 of the prism and being substantially perpendicular to the prism seat 9. These curved 70 ends are preferably engaged by adjusting screws 16 which are mounted in the casing walls and operable from the exterior of the casing, so that the prism 75 8 may be adjusted longitudinally of its seat. Preferably the screws 16 are mounted in brass bushings 17, as it has been found that the walls of the casing, which are usually made of aluminum, do not provide a strong anchorage for the adjusting screws. 85

To hold the prism to its seat a leaf spring 18 may be employed, this spring engaging the portion 11 of the cover substantially midway between its ends, and having its ends fitted in recesses 19 in the casing wall at 90 opposite ends of the prism seat. In this instance, these recesses are constructed by providing projections 20 on the casing walls and recessing the under side of the projections so that the recesses open toward the prism 95 seat, thus holding the ends of the spring against movement in any direction except in the direction of the prism seat. In this latter direction, the spring can be moved only against its spring action, and, as a consequence, while the removal of the spring is secured, the spring is held against accidental displacement. 100

The prism 7 is mounted in the same man-

ner as the prism 8, and, in addition, has provision for lateral adjustment, this being desirable in order that collimation of the instrument may be secured as well as 5 parallelism between the optical axes of the two halves of a binocular. The prism seat 9^a of the prism 7 is wider than the prism in order that the latter may partake of lateral or sidewise movement. Preferably 10 to one side of the center of the prism a bearing 21 is provided for engaging with one side wall of the prism 7. This bearing, in this instance, is in the form of a screw extending perpendicular to the prism seat 9^a, 15 but it will be apparent that any stationary bearing will serve the same function. Arranged at the opposite side of the prism seat 9^a is an adjustable bearing 22 which is in a line with the stationary bearing 21 at 20 right angles to the longitudinal axis of the prism seat. The prism 7 is first secured between the bearing 21 and the bearing 22 in a manner such that all play is eliminated, yet the prism is not placed under tension. 25 On the opposite side of the center of the prism two adjustable bearings 23 and 24 are provided, these bearings being situated upon opposite sides of the prism seat so as to engage opposite sides of the prism 7 sub- 30 stantially in a line at right angles to the longitudinal axis of the prism seat. It is apparent that, after the prism has been engaged by the bearings 21 and 22, it may be shifted laterally between said bearings by 35 the bearings 23 and 24, thus making it possible to effect the lateral adjustment of the prism for collimation of the instrument.

From the foregoing it will be seen that there has been provided a prism adjustment 40 in which the adjusting screws engage a portion of a device which engages with the curved end walls of the prism. By this arrangement pressure is not imposed on the angularly arranged faces of the prism, and 45 as a consequence the tendency to distort the prism through the devices for effecting the longitudinal adjustment is obviated. The prism is held to its seat by a spring which is secured at its end without the pro- 50 vision of separate fastening devices, being held in recesses formed in the walls of the casing and opening toward the prism seat, thus permitting the holding spring to be readily removed. The devices for effecting 55 the lateral adjustment of the prism are readily adjustable from the exterior of the casing and permit of such fine adjustment that a perfect collimation of the instrument is secured.

60 What I claim as my invention and desire to secure by Letters Patent is:—

1. In combination in an optical instrument, a seat, a prism arranged on the seat having two angularly-arranged faces and 65 curved end walls at the ends of said faces,

a device covering said faces and engaging said curved end walls, and adjusting devices coöperating with said device.

2. In combination in an optical instrument, a seat, a prism arranged on the seat 70 and having two angularly-arranged faces and curved end walls, a cover for said angularly-arranged faces having curved portions at opposite ends perpendicular to the prism seat and engaging the curved end 75 walls of the prism, and adjusting devices coöperating with the curved end walls of the cover.

3. In combination in an optical instrument, a seat, a prism arranged on the seat 80 and having two angularly-arranged faces, a cover for said angularly arranged faces of said prism having walls perpendicular to said seat, and adjusting devices for coöperating 85 with said perpendicular walls.

4. In combination in an optical instrument, a seat, a prism arranged on the seat having angularly arranged faces and curved end walls, a device having two portions perpendicular to the seat and coöperating with 90 the curved end walls, and adjusting screws engaging said perpendicular portions to adjust the prism on its seat.

5. In combination in an optical instrument, a casing having a prism seat therein 95 and recesses in the walls at opposite ends of said seat, said recesses opening laterally on the sides toward the prism seat, a prism resting on the seat and a spring strip coöperating with the prism between its ends 100 and having its ends received within the recesses of the casing and movable laterally toward the prism seat to be disengaged from the casing.

6. In combination in an optical instrument, a prism seat, a prism resting on said seat and having a pair of angularly-arranged faces, two bearings coöperating with opposite sides of the prism substantially in 110 a line transversely of the prism to serve as fulcrums, and two other bearings adjustably mounted to coöperate with opposite sides of the prism to one side of the first named bearings.

7. In combination in an optical instrument, a prism seat, a prism resting on the seat, and having a pair of angularly-arranged faces, two bearing points coöperating with opposite sides of the prism on a line at right angles to the longitudinal axis 120 of the prism, one of said bearings being adjustable and the other being stationary, and two bearings adjustably mounted to one side of the first named bearings to coöperate with opposite sides of the prism in order to swing 125 the latter between the first named two bearings.

8. In combination in an optical instrument, a casing having a prism seat, a prism resting on the seat and having a pair of 130

angularly arranged faces, a frame coöperating with the two angularly arranged faces and having two faces thereon substantially perpendicular to the seat, the distances between said faces being substantially equal to the length of the prism, and two devices for effecting the longitudinal adjustment of the prism mounted on the casing at opposite

ends of the prism and detachably engaging with said faces of the frame so that the latter and the prism may be removed from the casing by the release of one of such devices without disturbing the position of the other adjusting device.

FRANK MIHALYI.
